UNITED STATES PATENT OFFICE

RALPH PLUMB, OF BUFFALO, NEW YORK, ASSIGNOR TO BUFFALO BOLT COMPANY, OF NORTH TONAWANDA, NEW YORK, A CORPORATION OF NEW YORK

METHOD OF AND APPARATUS FOR MAKING THREADED BOLTS

Application filed January 26, 1926. Serial No. 83,778.

My present invention is shown as embodied in apparatus designed to make a great saving in cost of labor and to save one re-heat in hot-shaping and roll-threading of bolts made 5 from iron or steel bars or rods.

So far as concerns the apparatus for heating the coil or rod material, feeding it into the automatic cut-off, shank-forming and head-forming machine, these may be any of 10 the standard types commonly employed for hot forging of bolt blanks, the novel feature of the method being immediate transfer of the blanks to automatic hot bolt feeding mechanism so that by mechanism alone and 15 without any delay, the hot bolt blanks are deposited, one at a time, between their rolling platens which roll the thread on the shank, at one pass, and drop the bolt into a tempering bath.

20 The novel part of the mechanism between the hot bolt blanking machine and the bath comprises a bolt train feed means, whereby the bolts are caused to hang by the heads, shank down, between inclined guideways, the 25 latter being preferably rotary so as to avoid sticking and minimize friction of the bolt heads on said guides. Provision is made for freeing of the heads of the bolts over the funnel wherein they fall, shank down, and are 30 guided into operative registry with the thread rolling pass. The bolt, with its lower end supported on a suitable stop, has its shank maintained upright by a guideway end of the funnel, the latter having automatically 35 yieldable sections whereby the bolt may be bodily and forcibly carried laterally on a vertical axis between the automatically opening sections of the guide, the latter closing automatically when clear of the bolt.

40 As it is sometimes possible for a bolt to stick in the rolling platens, being thereby carried back to the funnel, the latter is prevented from damage by any such bolt by pivotally supporting the same from its upper end, so 45 that it can swivel rearwardly when engaged by such a bolt. Preferably, a single weight arm is utilized to non-positively return both the movable guide sections, and the pivoted funnel as a whole, to normal position.

50 The above and other features of my ap-

paratus may be better understood from the following description in connection with the accompanying drawings, in which

Fig. 1 is a side elevation of the mechanism for sorting and feeding the hot bolts, one by 55 one, to the screw forming platens, the conveyor from the hot bolt-blanking machine being shown in section;

Fig. 2 is a top plan view, the hot bolt conveyor and the hopper sides being removed; 60

Fig. 3 is a section on the line 3—3, Fig. 1, viewing endwise the sorting rolls and the hopper for retaining the hot bolts in operative relation to the guide-way opening between the rolls; 65

Fig. 4 is a section on the line 4—4, Fig. 2, showing the escapement mechanism for one by one release of the bolts in the guideway;

Fig. 5 is a view of the mechanism from the lower end thereof; 70

Fig. 6 is a vertical section on the line 6—6, Fig. 1, showing the relation of the bolt supplying roller guide-way, the funnel, and the thread-rolling platens;

Fig. 7 is a vertical section through the 75 funnel on the line 7—7;

Fig. 8 is a horizontal section through the funnel on the line 8—8, Fig. 7; and

Fig. 9 is a plan view of the thread-rolling platens showing the relation to a bolt in the 80 funnel and to a tempering bath into which the completed bolts fall.

As indicated by the legend on Fig. 1, the hot bolt blanks from the bolt header are immediately conveyed through trough 1, whence 85 they are deflected through opening 2, and down between hopper walls, 5, 6 (Fig. 3), whereby they are retained above the slot-like pass, 7, between the rolls 8 and 9 (Fig. 2). In this position, the bolts that may be 90 bunched are beaten back by toothed roller, 10, supported in a bracket, 11, and continuously driven counter-clock-wise through pulley, 12. The bracket, 11, is secured to the main frame, 13, which supports the conveyor, 95 1. The main frame also supports the bracket, 15, at the upper end, and a similar bracket, 16, at the lower end, in which roller guide 9 is rotatably mounted. The other roller guide, 8, is mounted in the upper and lower bracket 100

arms, 15^a, 16^a, which are pivotally and adjustably secured to the brackets, 15 and 16, respectively.

The rolls preferably rotate from each other, 5 power for driving them being applied at the upper end, through a suitably driven shaft 20, bevel gears, 21, 22 and shaft, 23. Gear 24, on the shaft 23, drives directly through gear 25 on roll 9 and through intermediate gear 26 on a stud coaxial with the pivot of the bracket arm, 15^a, it drives gear 27 on roll 8. The width of the guide slot, 7, between the rolls is adjusted by means of bolts 30 and 31, engaging ears, 32, 33, on the upper 15 and lower brackets, 15^a, 16^a, respectively. These bolts extend through the main frame, 13, and are clamped on opposite sides thereof by nuts, 34. Their free ends are clamped on opposite sides of ears 32, 33, by nuts 35.

20 The roller guides are adjusted so that the slot 7 between them is of the proper diameter to permit the shanks of the bolts to fall down between them so that the bolts hang by their heads as indicated in Fig. 4. The general 25 alignment of the bolts with the slot is preserved by means of the hopper sides, 5, 6, shown in Fig. 3 and the tooth wheel, 10, operates as a kicker engaging any bolt that falls on top of another, but the clearance be- 30 low 10 is sufficient to permit passage of all bolts hanging properly by their heads, so it is only necessary to keep up the supply of hot bolts in order to preserve a train of the bolts α in a position shown in Fig. 4. The 35 inclination of the rolls and their rotation operates to maintain the bolts pressing one against another and their further progress to the threading dies is controlled by separating and release mechanism.

40 As shown in Figs. 2 and 4, there is an escapement comprising an upper finger, 40, and a lower finger, 41, the free ends of which are formed with flat front faces, reciprocating into and out of the path of the shanks of the 45 bolts as they travel down the roller guides, 8, 9. They are timed so that each is projected forward into the bolt engaging position when the other retreats to release the bolt, and their rear surfaces are formed with 50 wedge surfaces, 43, so that each wedges forward the shank of each bolt in its progress down the guideway. These escapement wedge members are on the ends of slides 44, 45, mounted in bracket, 46, on the rear of 55 frame 13. The slides have pivots, 47, 48, encircled by links, 49, 50, rocking on pivots, 53, 54, in the upper ends of arms, 55, 56, having anti-friction rolls 57, 58, engaging re- 60 tracting cams 60, 61, on shaft, 62, which is mounted in standard, 64, and is driven through beveled gears, 65 and 66, and shaft 67, from a source of power synchronized with the thread-rolling die. As best shown in Fig. 65 4, the retracting cams 60, 61, are similar in form, but opposite in phase, to produce the

overlapping, alternating stop operation of the fingers, 40, 41, and in their forward movement, said fingers are actuated by springs, as 66, which are shown in Fig. 4 as secured to bracket 46 at one end and to arm 56 at the 70 other end.

Bolts released by the lower stop finger, 41, are permitted to fall through the guideway by correspondingly timed mechanism operating to withdraw the guide support for the 75 heads of the bolts. As shown in Fig. 2, and more in detail in Fig. 7, the rolls, 8, 9, have reduced extensions, 8^a, 9^a, having sleeves, 8^b, 9^b, of the same diameter as the rolls, slidably secured to but rotating with said rolls through 80 the medium of a spline 9^c (Fig. 7). The sleeves, 8^b, 9^b, are rotatably mounted in bearings, 8^d, 9^d, in a yoke, 70, having trunnions, 71, 71, engaging bearings, 72, 72, in the ends of arms, 73, 73, which are keyed to shaft 74, 85 said shaft being supported rotatably in a bearing, 75, secured to the frame 13 by bracket 76. Shaft 74 has also keyed thereto an arm, 77, which is oscillated by arm, 78 (Fig. 2), which is loosely mounted on shaft 74, the 90 relation of parts being such that arm, 77, is positively retracted by 78, but the coupling is non-positive for the restoring movement, being through the medium of a compression spring, 79, on bolt, 80, retained by nut, 81, at the outer end, extending through 78 and retained at the other end by nut, 82. This arm carries an anti-friction roller, 83, engaging the cam slot, 84, formed intermediate the adjacent surfaces of rotors, 85 and 86, mounted upon and driven by the same shaft, 62, that rotates the escapement cams first above described. The phase relation of the cam slot, 84, to the escapement cams, 60, 61, is such that the retracting of yoke, 70, and with it the guide sleeves, 8^b, 9^b, occurs exactly at the time a bolt is released by the lower finger, 41. Being thus released, the bolt falls, shank first, into the funnel, 90.

The funnel, 90, is pivotally mounted (see 110 Fig. 6) on a lateral stud, 91, to which it is rigidly secured as by pin, 92. This stud is journaled in a sleeve, 93, extending through the main frame, 13, the sleeve being secured by lock nut, 94, and the stud being prevented, 115 from endwise removal by jam nuts, 95.

As shown in Figs. 6 and 7, the funnel has a rear slot, 96 extending downward a distance sufficient to admit the longest bolt for which the machine is designed, and it is formed at the lower end with a converging portion, the rear half, 97, being integral with the funnel, but the forward portion comprising vertical sections, 98, 99, mounted on vertical pivots 100, 101 (see Fig. 8), on the rear of integral funnel section 97. The sections, 98, 99, are yieldingly held in the closed position by a bell crank lever, comprising depending arms, 102, 103, bearing on cam projections, 104, 105. The other arm, 106, of 120 125 130

the bell crank extends rearwardly and carries a weight, 107. This bell crank is mounted on a pivot, 108, on the rear of the funnel section. As the funnel is carried by the pivot 91 at the upper end thereof and as its operating position is vertical, it is prevented from forward swing under pressure of the eccentric weight, 107, by suitable means as, for instance, a stop, 109, on frame 18. As shown in Fig. 8, the hinge sections, 98, 99, have their forward adjacent edges formed with the lower portions 98^a, 99^a, adapted to form yielding lateral guides for the shank of the bolt while higher up the opening is wider to perform a similar function for the head of the bolt.

The bolts falling into the funnel are guided to the pass between thread-rolling dies of any known or desired type, a stationary member, 110 and a reciprocating member, 111, being shown in Figs. 6 and 9. The shank end of the bolt projecting through the funnel falls on the stop, 113, on the upper edge of which it rests until the slide, 111, is in its rearward position and the thread-rolling pass is thus opened for reception of the bolt. In this position, the stop, 113, being retracted, the bolt falls endwise, onto gauge stop, 114, which is supported from the stationary die, at the proper depth in the pass, the bolt being guided during its fall by the lower portion of the funnel guide. Then upon forward movement of slide 111, the bolt is nipped and rolled in upright position between the thread surfaces of stationary and movable die. As it rolls forward, its upper end forces its way out of the funnel through the lateral guide sections, 98, 99, which yieldingly open, applying pressure against the bell crank arms, 100, 101, thereby lifting weight 107.

At the end of the pass, the thread has been rolled in the bolt and the rear end of die 111 being then clear of the forward end of the stationary die 110, the bolt falls free, as indicated in dotted lines at α , Fig. 9. It falls into a tempering bath, while still at the high luminous heat required for tempering, this being the original heat which was given before entering the blank-forming header which supplies the conveyor 1.

If for any reason the bolt sticks to the movable die and is rolled back therewith so that it strikes the funnel guide, the latter can pivot about 91 and will be by gravity returned to its position against stop 109 by the weight, 107, which thus serves as yielding support not only for yieldably closing the vertically pivoted guide sections, 98, 99, but also for yieldingly restoring the horizontally pivoted funnel, 96.

The bolt entraining guides, 5, 6, together with the converging sides of adjacent rollers, 8, 9, form a slot-bottomed hopper of considerable storage capacity, and in the preferred

operation this contributes an equalizing or averaging effect ensuring uniform rate supply of bolts to the rolling dies even though there be considerable irregularity or bunching of the bolts as they come through the conveyor 1, from the hot bolt machine or other source of supply.

In the preferred operation, however, it is desirable to maintain the supply of bolts through the conveyor 1, quite uniform, and to operate the thread-rolling mechanism at a speed sufficient to take care of the supply so that the entrained bolts on the guide-rollers, 8, 9, will not accumulate and remain for a time long enough to permit cooling thereof below the tempering heat.

It is obvious that the bolt entraining and feeding mechanism may be used for cold bolt blanks or even for completely formed and threaded bolts which it is desired to present in orderly manner and at controllable rate to mechanisms other than threading dies.

Similarly, the mechanism may be used for other headed articles having heads substantially larger than the shanks.

I claim:

1. A bolt-threading machine, comprising relatively reciprocating threading platens between which the bolt blank is rolled, in combination with automatic mechanism for entraining the bolt blanks and guiding them to operative position in the pass between said platens, said mechanism including parallel inclined rolls spaced apart to hold the heads while permitting passage of the shanks of the bolt blanks.

2. A bolt-threading machine, comprising relatively reciprocating threading platens between which the bolt blank is rolled, in combination with automatic mechanism for entraining the bolt blanks and guiding them to operative position in the pass between said platens, said mechanism including parallel inclined rolls spaced apart to hold the heads while permitting passage of the shanks of the bolt blanks and escapement mechanism for one by one release of the bolts traveling down said inclined rolls and for then releasing the heads of said bolts.

3. A bolt-threading machine, comprising relatively reciprocating threading platens between which the bolt blank is rolled, in combination with automatic mechanism for entraining the bolt blanks and guiding them to operative position in the pass between said platens and means for controlling the length of bolt shank engaging the threading platens.

4. A bolt-threading machine, comprising co-operative, stationary and reciprocating, threading platens adapted to receive and roll the bolt blank with its axis vertical, in combination with automatic hot bolt supplying means and guide means having its outlet presenting the bolts vertically, shank downward, at the entrance of the pass between the plat-

ens and means for controlling the length of bolt shank engaging the threading platens.

5. A bolt-threading machine, comprising co-operative, stationary and reciprocating, 5 threading platens adapted to receive and roll the bolt blank with its axis vertical, in combination with guide means having its outlet presenting the bolts vertically, shank downward, at the entrance of the pass between the platens, said guide means having its forward walls yieldably closed to permit automatic opening thereof by the bolt blank when rolled between the dies.

6. A bolt-threading machine, comprising 15 co-operative, stationary and reciprocating, threading platens adapted to receive and roll the bolt blank with its axis vertical, in combination with guide means having its outlet presenting the bolts vertically, shank downward, at the entrance of the pass between the platens, said guide means having its forward walls yieldably closed to permit automatic opening thereof by the bolt blank when rolled between the dies, the upper end of said 20 guide means being pivoted on a horizontal axis to permit rearward swinging of the lower end thereof when engaged by a returning bolt caught in the movable platen.

7. A bolt-threading machine, comprising 30 co-operative, stationary and reciprocating, threading platens adapted to receive and roll the bolt blank with its axis vertical, in combination with guide means having its outlet presenting the bolts vertically, shank downward, at the entrance of the pass between the platens, the forward lower wall of said guide means being formed by vertically pivoted sections adapted to open in the plane of the pass, and means for holding them yieldably closed, 35 comprising a bell crank supported on a horizontal pivot and having one arm extending rearwardly with a weight thereon and other arms engaging said pivotally mounted sections.

45 8. A bolt-threading machine, comprising co-operative, stationary and reciprocating, threading platens adapted to receive and roll the bolt blank with its axis vertical, in combination with guide means having its outlet 50 presenting the bolts vertically, shank downward, at the entrance of the pass between the platens, the forward lower wall of said guide means being formed by vertically pivoted sections adapted to open in the plane of the pass, and means for holding them yieldably closed, comprising a bell crank supported 55 on a horizontal pivot and having one arm extending rearwardly with a weight thereon and other arms engaging said pivotally mounted sections, and said guide, as a whole being pivoted on a horizontal axis to permit rearward swinging of the lower end thereof when engaged by a returning bolt caught in the movable platen.

55 9. A bolt-threading machine, comprising

cooperative, stationary and reciprocating, threading platens adapted to receive and roll the bolt blank with its axis vertical, in combination with guide means having its outlet presenting the bolts vertically, shank downward, at the entrance of the pass between the platens, said guide means being pivoted on a horizontal axis to permit rearward swinging of the lower end thereof when engaged by a returning bolt caught in the movable platen.

10. Apparatus for bolts or the like, including a slot-bottomed hopper the bottom of which is formed by parallel rolls spaced apart to pass the shanks while retaining the heads of the bolts, and means for rotating said rolls.

11. Apparatus for bolts or the like, including a slot-bottomed hopper the bottom of which is formed by parallel rolls spaced apart to pass the shanks while retaining the heads of the bolts, and means for rotating said rolls in opposite directions.

12. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other.

13. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward.

14. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward, in combination with a rotary kicker turning upward at the outlet of the hopper with clearance sufficient to permit passage of the heads of properly entrained bolts.

15. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward, in combination with a rotary kicker turning up-

ward at the outlet of the hopper with clearance sufficient to permit passage of the heads of properly entrained bolts and, below the hopper, bolt-separating escapement mechanism for passing the bolts, one at a time, while holding back bolts in train behind the escapement.

16. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward and, below the hopper, bolt-separating escapement mechanism for passing the bolts, one at a time, while holding back bolts in train behind the escapement.

17. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward and, below the hopper, bolt-separating escapement mechanism for passing the bolts, one at a time, while holding back bolts in train behind the escapement, said rolls being formed with sections slidable endwise to permit dropping of the bolt heads therethrough.

18. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward, said rolls being formed with sections slidable endwise to permit dropping of the bolt heads therethrough.

19. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward and, below the hopper, bolt-separating escapement mechanism for passing the bolts, one at a time, while holding back bolts in train behind the escapement, said rolls being formed with sections slidable endwise to permit dropping

of the bolt heads therethrough, together with mechanism for operating the latter and said escapement in synchronous relation, a funnel guide into which said bolts fall, shank downward and mechanism in operative relation for receiving the bolts from the lower end of the funnel.

20. Apparatus for bolts or the like, including a slot-bottomed hopper the bottom of which is formed by parallel rolls spaced apart to pass the shanks while retaining the heads of the bolts, and means for rotating said rolls in opposite directions, with their adjacent bolt-engaging surfaces rotating upwardly and away from each other, said rollers having their axes inclined so that bolts properly entrained in the slots slide downward, said rolls being formed with sections slidable endwise to permit dropping of the bolt heads therethrough, together with mechanism for operating the latter and said escapement in synchronous relation, a funnel guide into which said bolts fall, shank downward and mechanism in operative relation for receiving the bolts from the lower end of the funnel.

21. The method of making bolts, which includes heating a bar or rod white hot throughout, feeding it directly to a high speed automatic bolt-blanking machine to produce a succession of white hot bolt blanks, entraining the blanks, shank downward, dropping them to the entrance of the pass between reciprocating threading dies, while maintaining an approximate vertical position of the blanks, dropping the blanks further, the required distance into the pass when the movable threading die is at the beginning of its forward stroke, utilizing the forward movement of said die to simultaneously form the thread and roll the bolt to the exit of the pass between the dies and, while still at high luminous temperature, receiving the discharged blank in a tempering bath.

Signed at North Tonawanda in the county of Niagara and State of New York, this 19th day of January, A. D. 1926.

RALPH PLUMB.
